UNITED STATES PATENT OFFICE.

JOHN W. METZ, OF MANCHESTER, OHIO.

SAFETY-BRAKE FOR ELEVATORS.

SPECIFICATION forming part of Letters Patent No. 324,144, dated August 11, 1885.

Application filed June 5, 1885. (No model.)

To all whom it may concern:

Be it known that I, JOHN W. METZ, of Manchester, in the county of Adams and State of Ohio, have invented a new and Improved 5 Safety-Brake for Elevators, of which the following is a full, clear, and exact description.

My invention relates to elevators, and particularly to safety brakes or stops therefor, and has for its object to provide simple, inexpensive, and efficient means for stopping the elevator-carriage should the hoisting-rope break or other accident occur.

The invention consists in a novel construction and arrangement of cam-headed grip-levers and operating-levers, both pivoted to the elevator-carriage, and connected by links and by pull-cords leading to the carriage within reach of its occupants, who may by pulling on the cords cause the grip-levers to take hold of 20 the carriage guide-posts or ways and stop the carriage, all as hereinafter fully described and claimed.

Reference is to be had to the accompanying drawings, forming part of this specification, 25 in which similar letters of reference indicate corresponding parts in all the figures.

Figure 1 is a side elevation of an elevator-carriage fitted with my improved safety-brake, and showing also the opposite side walls, and 30 one of the guide-posts of the carriage in section and the brake out of use. Fig. 2 is a detail side view illustrating the safety-brake applied at one side of one guide-post, and illustrating the operation of the brake in stopping 35 the carriage. Fig. 3 is a view at right angles to Fig. 1, and showing the same parts; and Fig. 4 is a perspective view of the hand-grasp and pull-cords arranged therewith for double brakes at each side of the carriage.

40 The letter A indicates the elevator carriage or cage, which has a platform, a, side posts a' a', and head-piece a'', to which the hoisting-rope B is attached in any approved way. The carriage side posts, a' a', have attached to 45 them the lugs or plates C which work along each side of the guide posts or ways D D, fitted at and along opposite sides of the elevator-shaft, to guide the carriage in its movements up and down the shaft.

50 In the preferred arrangement of the safety-brake devices I use them one at each side of

each guide post D of the carriage, as illustrated most clearly in Fig. 1 and next described.

On strong pins e e fixed in the side of the 55 platform a of carriage A, and a short distance from the guide-posts D, are pivoted the grip or stop levers E, which have eccentric or cam heads F provided on their cam-faces, which are presented to the posts D with teeth f which 60 are adapted to bite into the posts D, as presently described. The grip-levers E extend outward from the posts D, and are connected at their outer ends by links G, with their operating-levers H, which are pivoted at h about 65 at their centers to the carriage-platform, and carry at their inner ends the weights I, which normally act to raise the outer ends of grip-levers E, and keep their cam-heads F away 70 from the guide-posts, so that the carriage A will move freely up and down the elevator-shaft.

To the weighted end of each of the levers H is connected the end of a cord, rope, or chain, J, which passes upward to and over guide-pulleys K, journaled in keepers k or otherwise, to the side posts, a', of the carriage A, and from said pulleys the cords J pass to a hand-grasp, L, which is supported by the cords near the top of the carriage, as in Fig. 3, or so as to be 80 within reach of the occupants of the carriage.

The hand-grasp L may be of any suitable construction, and the pull-cords may be attached to it in any approved way, but I prefer to make the hand-grasp of a piece of metal 85 tubing or pipe, and to pass the cords J in a loop around one side of the hand-grasp, so that one cord really forms the two opposite pull-cords J J, for operating the pair of levers H H at the front of the opposite guide-posts D D, and another cord forms the other two pull-cords operating the pair of levers H H at the rear of the guide posts. (See Figs. 3 and 4.)

It is evident that should the hoisting-rope 95 B break and the carriage be free to fall, or if for any other reason it is desired to stop the movement of the elevator-carriage, it only is necessary to pull on the hand-grasp L, which will operate the levers H to force the outer 100 ends of levers E downward, and carry the gripping-faces of their cam-heads F against

the carriage guide-posts D, and instantly or almost instantly stop the carriage.

When the levers E H are arranged at one side only of the opposite guide-posts, D D, 5 heavy blocks or dead stops M will be fixed to the carriage-platform at the opposite faces of the guide-posts, as shown in Fig. 2, and when the hand-grasp L is pulled to draw on the cords J the levers E will forcibly draw the stops M to the posts D as they take a biting-grip on the opposite faces of the posts by their cam-heads F.

Upon releasing or letting go of the hand-grasp L the weights I of levers H will draw them back to horizontal position, and release the cams F from the guide-posts D, as will be readily understood.

Having thus described my invention, what I claim as new, and desire to secure by Letters 20 Patent, is—

1. A safety-brake for elevators, consisting of the levers E, pivoted at their inner ends to the carriage, and having cam-heads F for engaging guide-posts, the weighted levers H, pivoted a little at one side of the center of their 25 length, the links G, connecting the outer ends of the said levers, and the pull-cords J, attached to the inner ends of the levers H, substantially as herein shown and described.

2. The combination, in a safety-brake for 30 elevators and with the carriage A and its guide posts or ways D, of levers E H, pull-cords J, pulleys K, and hand-grasp L, substantially as herein set forth.

JOHN W. METZ.
